COMBINED BILLFOLD AND CARD CASE

Orval C. Sheets, Cape Girardeau, Mo., assignor to Clarence Whitman & Sons, Inc., St. Louis, Mo., a corporation of Pennsylvania

Application October 14, 1955, Serial No. 38,372

Term of patent 14 years

(Cl. D87—3)

FIG.3.

FIG.4.

FIG.2.

FIG.5.

FIG.7.

FIG.6.

Fig. 1 is a side elevational view of a combined billfold and card case showing my new design for the outer or rear side thereof,

Fig. 2 is a side elevational view of a combined billfold and card case showing my new design for the inner sides thereof,

Fig. 3 is an edge view of the combined billfold and card case in its open or extended adjustment,

Fig. 4 is a left end elevational view of the combined billfold and card case shown in Fig. 2,

Fig. 5 is a right end elevational view of the combined billfold and card case shown in Fig. 2,

Fig. 6 is a perspective view of the combined billfold with the card opened showing my new design, and

Fig. 7 is a fragmentary elevational view of the card case shown in the open or extended adjustment on the combined billfold and card case.

I claim:

The ornamental design for a combined billfold and card case, substantially as shown and described.
